No. 37,426.

Patented May 9, 1905.

UNITED STATES PATENT OFFICE.

ERNST GOTHLBERG, OF JERSEY CITY, NEW JERSEY.

DESIGN FOR A CHANDELIER-BODY.

SPECIFICATION forming part of Design No. 37,426, dated May 9, 1905.

Application filed March 22, 1905. Serial No. 251,512. Term of patent 3½ years.

To all whom it may concern:

Be it known that I, ERNST GOTHLBERG, a citizen of the United States, residing in Jersey City, in the county of Hudson and State of New Jersey, have invented a new, original, and ornamental Design for Chandelier-Bodies, of which the following is a specification, reference being had to the accompanying drawings, forming a part thereof.

Figure 1 is a side elevation of a chandelier-body, showing my design. Fig. 2 is a top plan view thereof.

I claim—

The ornamental design for a chandelier-body, as shown.

ERNST GOTHLBERG.
